UNITED STATES PATENT OFFICE.

DAVID L. A. LARSONNEUR, OF CHICAGO, ILLINOIS.

GOVERNOR.

Application filed January 31, 1920. Serial No. 355,424.

To all whom it may concern:

Be it known that I, DAVID L. A. LARSONNEUR, a citizen of the United States, residing at Chicago, in the county of Cook and State of Illinois, have invented certain new and useful Improvements in Governors, of which the following is a description.

My invention relates to that general class of devices known as governors, and relates particularly to an improved governor for internal combustion engines or the like. The invention has among its objects the production of a simple, practical, compact, durable, efficient and satisfactory governor of the kind described, for use wherever found applicable. It has particularly as an object the production of a simple governor which may be adjusted as desired without disturbing the working parts, and which will automatically control the motor, the same working substantially instantaneously and noiselessly. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Figure 1 is a sectional view taken substantially on line 1—1 of Figure 2 of the preferred form of my device;

Figure 2 is a sectional view taken substantially on line 2—2 of Figure 1;

Figure 3 is a side elevation of a portion of the same;

Figure 4 is a sectional view taken substantially on line 4—4 of Figure 1;

Figure 5 is a sectional view taken substantially on line 5—5 of Figure 6 illustrating a modified controlling mechanism;

Figure 6 is a sectional view taken substantially on line 6—6 of Figure 5;

Figure 7 is a sectional view taken substantially on line 7—7 of Figure 8 illustrating another modified mechanism;

Figure 8 is a sectional view taken substantially on line 8—8 of Figure 7; and

Figure 9 is a sectional view similar to Figure 5 illustrating another modified construction.

Referring to the drawings, 1 represents a

suitable casing of the desired size, shape and material which may be provided with a flange 2 at the inlet end and a flange 3 at the outlet end for convenience in attaching the device to the engine, the same being placed between the carbureter and the engine intake port. As shown, the casing is slightly enlarged as at 4, and formed with the valve seat as at 5. Arranged to cooperate with the valve seat 5 is a valve member 6, preferably constructed substantially as shown, and which is slidably mounted on a guide rod 8, carried by a member 7, or its equivalent. I have shown the valve rod or guide 8 braced at its upper end by means of member 9, which, when employed, may be of the desired size and shape, preferably so that it does not impede the flow of the mixture passing through the casing. The valve is normally maintained open and in the position, as shown in Figures 1 and 2, by a spring 10 bearing against the valve and against a member 11.

In the construction shown in Figures 1 and 2, member 11 is extended and provided with teeth 12 arranged to cooperate with a small pinion 13 on a shaft or rod 14, which projects to the exterior of the casing and is provided with a part 15 secured thereto, which part may be locked in the desired position, thereby maintaining part 11 substantially rigid. As shown, the part 15 is flanged as at 15', and formed with slots 17 through which pass screws 18, or the equivalent, by means of which part 15 may be adjusted and secured in place to provide a desired adjustment. The part 15 and the screws 18 may be secured against tampering or unauthorized adjusting by means of a wire 20 and seal 20', it being understood that any equivalent may be provided for the purpose. Arranged at the inlet end of the casing I provide a Venturi tube 16, which has a tendency to cause a thorough mixture or co-mixture of the passing charge as it passes through the governor, thereby increasing the efficiency of the mixture. The valve also has a tendency to increase the mixing. If desired, ports or openings 19 may be arranged as shown, the number of the same, as well as the size, being as preferred. These permit the passage of a portion of the mixture through the governor when the valve is entirely closed, so that at least some charge will pass to the engine and prevent its stopping, or as it is termed, "being killed."

In using the device, the same is installed as before mentioned, between the carbureter and the engine, and the member 11 set at the desired point to give the desired tension on the spring 10. When the engine is speeded up, the passing mixture, owing to its high velocity, tends to move the valve toward its closed position, thereby shutting off a portion of the mixture to the engine, 10 causing it to slow down. The member 11 may be so adjusted as to give just the desired tension on the spring so that the device will operate when the engine reaches the speed which it is desired as the maximum, at the 15 time the valve will be shut. It will be noted that the device consists of but few parts, and that there are no pockets or projecting parts which will collect or pocket the vapor, causing condensation and accumulation of 20 the gases or hydro-carbon particles. The parts are so designed and constructed that the device at the same time not only does not impede the passage of the mixture, but has a tendency to cause a thorough mixing 25 action, thereby improving the charge.

In the construction shown in Figures 5 and 6, 21 represents the casing, 22 the upper flange, 23 the rod, and 24 the spring. Arranged on the rod and bearing against the 30 spring is a member 25 which is arranged to be controlled by a cam member or members 26, mounted on the shaft or rod 27, and secured thereon by screw 28, or equivalent means. Rod 27 is secured to a member 29 corresponding to the member 15 shown in Figure 1. Obviously, operating the rod 27 operates the cam 26, thereby adjusting the tension of the spring. In Figures 7 and 35 8, 31 represents the casing, 32 its flange, 33 the rod or stem, and 34 the spring. Member 35, mounted upon the rod, is arranged to cooperate with spring 34 and an arm 36 mounted on a rod 37, provided with a part 38. Obviously, turning the rod 37 controls member 35 and regulates the pressure or 40 tension of the spring.

In Figure 9, 41 represents the casing, 43 the valve stem or rod upon which the valve is mounted, 44 the spring, and 45 the member mounted on the rod. In this case, member 45 is provided with an internal thread arranged to engage with the thread 47 on the rod 43, and is provided with an extending part 46, provided with spiral thread 49 arranged to mesh with the spiral thread 49 on the rod 48. Rod 48 is provided with an end 50 similar to that previously described. With this construction, rotation of the rod 48 causes a rotation of member 45 which is in 55 threaded engagement with rod 43, and the same adjusts up and down on the rod, regulating the pressure of the spring.

It will be particularly noted in the preceding that the device may be so adjusted and controlled on the exterior of the casing that any given speed will cause the valve to close or partially close, thereby controlling or regulating the operation of the engine. The device may be locked against tampering.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A governor of the character described comprising a casing having an inlet and an outlet with a widened portion intermediate said inlet and said outlet, a valve supporting stem disposed within the casing, a valve slidably mounted on said stem, an extension projecting into the widened portion of the casing, said extension contacting with the valve when the same is in a closed position, a plurality of apertures passing through said extension to provide a passageway when the valve is closed, a spring for normally urging said valve in an open position, and means for varying the pressure necessary to close the valve.

2. A governor of the character described comprising a casing having an inlet and an outlet with a widened portion intermediate said inlet and said outlet, a valve supporting stem disposed within the casing, a valve slidably mounted on said stem, an extension projecting into the widened portion of the casing, said valve when in a closed position abutting against the extension, a plurality of apertures passing through said extension to provide a passageway when the valve is closed, a spring for normally urging said valve in an open position, and means for varying the pressure necessary to close the valve, said means comprising an elongated member having gear teeth thereon slidably mounted on the stem and a transverse member passing through said casing and having a pinion cooperating with said gear teeth for shifting said slidale member.

In testimony whereof, I have hereunto signed my name in the presence of two subscribing witnesses.

DAVID L. A. LARSONNEUR.
